United States Patent Office

Des. 225,808

Patented Jan. 9, 1973

225,808

STUDENT CARREL UNIT

Frank R. Torrey, 9805 Dallas Ave.,
Silver Spring, Md. 20901

Filed Feb. 19, 1971, Ser. No. 117,209

Term of patent 14 years

Int. Cl. D6—04

U.S. Cl. D6—181

FIG. 1

FIG. 2

FIG. 3

FIG. 4

FIG. 5

FIG. 6

FIG. 1 is a perspective view of a student carrel unit showing my new design;

FIG. 2 is a rear elevational view of the carrel shown in FIG. 1;

FIG. 3 is a right side elevational view of the carrel of FIG. 1, the left side being a mirror image thereof;

FIG. 4 is a perspective view of a modified form of the carrel unit;

FIG. 5 is a rear elevational view of the modified form shown in FIG. 4;

FIG. 6 is a right side elevational view of the modified form shown in FIG. 4, the left side being a mirror image thereof.

I claim:

The ornamental design for a student carrel unit, as shown and described.
